DESIGN FOR A LADY'S PRINCESS COSTUME.

2052

2052

UNITED STATES PATENT OFFICE.

ELLEN MORAN, OF NEW YORK, N. Y., ASSIGNOR TO THE BUTTERICK PUBLISHING COMPANY, (LIMITED,) OF SAME PLACE.

DESIGN FOR A LADY'S PRINCESS COSTUME.

SPECIFICATION forming part of Design No. 18,291, dated May 1, 1883.

Application filed April 12, 1883. Serial No. 269,382. Term of patent 3½ years.

To all whom it may concern:

Be it known that I, ELLEN MORAN, of the city, county, and State of New York, have invented and produced a new and original Design for a Pattern of a Lady's Princess Costume; and I do hereby declare that the engraved prints accompanying this specification convey to any one accustomed to using paper patterns a clear understanding of how a garment made up by the pattern will appear.

The design shows princess fronts that display a long polonaise front on the right side, extending diagonally from the top of the shoulder to below the waist-line and then straight to the lower edge, and exhibiting forward-turning plaits along its front edge, drap-

ing plaits below these plaits and in the right side edge, and a rounding lower outline; a close-fitting basque back describing a point at the lower edge, and exhibiting a full skirt depending from the point; a plain panel on the left front, a standing collar, and coat-sleeves.

What I claim as my invention, and desire to secure by Letters Patent, is—

The design for a lady's princess costume, as shown in the engraved prints accompanying this specification.

ELLEN MORAN.
